CLAIM

The ornamental design for a support stand for remote controllers, as shown and described.

DESCRIPTION

FIG. 1 is a perspective view of a support stand for remote controllers showing my new design; FIG. 2 is a side elevational view on an enlarged scale, the three sides not shown being identical in appearance thereto;

FIG. 3 is a top plan view on an enlarged scale; and FIG. 4 is a bottom plan view on an enlarged scale thereof.

FIG. 1

FIG. 2

FIG. 3

FIG. 4
